UNITED STATES PATENT OFFICE

HENRY HERMANI, OF BALTIMORE, MARYLAND, ASSIGNOR TO THE TIN DECORATING COMPANY OF BALTIMORE, OF BALTIMORE, MARYLAND, A CORPORATION OF NEW JERSEY

LUNCH KIT

Application filed June 16, 1928. Serial No. 285,959.

This invention is an improvement in lunch kits or boxes, and more particularly in an attachment for such devices for holding a vacuum walled bottle, or the like, in the top of the box or kit.

Since kits of the character in question are designed to be sold at low price, it is apparent that any attachment which materially increases the cost of the kit is not desirable.

10 In articles of the character heretofore constructed, holders for vacuum walled bottles and the like, for retaining the bottle in the top of the kit have been separate attachments, necessitating additional labor in the connection of the attachment.

15 A clasp is usually provided for partially embracing the bottle, and the clasp must be connected at one end to enable swinging of the clasp out of the way of the bottle during removal and replacement, and at the other end detachably to enable release of the clasp.

20 One of the primary objects of the present invention is the provision of a holder of the character specified, wherein the permanently connected end requires no additional connecting means, the connection being made directly with an element of a kit or box.

25 Another object is the provision of a clasp wherein the arrangement at the detachable end is such as to provide resiliency for enabling release, and a finger-piece for operating the releasing part of the clasp.

With these and other objects in view the invention consists in the construction and 30 novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—

35 Fig. 1 is a transverse vertical section of a kit provided with the improved clasp.

Fig. 2 is a plan view with the top open.

40 Fig. 3 is a perspective view of the kit closed, looking at the rear.

45 In the present embodiment of the invention, the kit or box is of usual construction,

comprising a body 1, of rectangular cross section, and a top 2 adapted to cooperate with the body to form a closure, and the top is rounded transversely as shown.

At one wall the top has bearings 3 which are adapted to align with similar bearings 4 on the adjacent wall of the body, to receive a pintle pin 5, which hingedly connects the top and body. In the present instance, the bearings 3 at the top are shown as integral, and the bearing 4 in the form of hinge leaves, but it is apparent that the bearings 4 might be integral as well as the bearings 3. Clasps of any desired construction indicated generally at 6 are provided for holding the top or cover closed.

The clasp is formed from a strip of sheet material, as for instance, sheet metal, having the central portion 7 thereof curved to fit the body of the vacuum walled bottle, or the like, indicated at 8. The ends are reversely curved on a shorter radius as indicated at 9 and 10 respectively, and the end 9 is provided with a bearing 11. Referring to Figs. 2 and 3, it will be noticed that the bottom or body 1 of the kit has two bearings 4, one near each end, while the top has two pairs of bearings, one on each side of each bearing 4. At the middle, there would normally be another bearing of the body 1, such bearing is omitted, and the bearing 11 of the clasp engages the pintle at this point. That is, where normally the bearings 3 and 4 would alternate, the central bearing is on the clasp 7, instead of on the body.

The opposite end 10 of the clasp is bent back substantially parallel with the reverse curve 10, as shown at 12, to provide a latch 13 in the form of a nose which is adapted to engage a catch 14, secured to the side wall 90 of the top, as for instance, by a rivet 15. The portion 12 of the clasp provides a finger-piece, by means of which the latch may be released, and the reverse curve 10 provides resiliency, enabling the latch to be released from the catch.

In operation, with the parts in the full line position of Fig. 1, when it is desired to release the vacuum walled bottle, the top is opened to the dotted line position. Down-

ward and inward pressure is made upon the finger-piece 12, releasing the latch from the catch, after which the clasp may be swung in the open position of Fig. 1, enabling removal of the vacuum walled bottle. When the bottle is replaced, downward pressure on the finger-piece 1 simultaneously moves the clasp into operative position, and engages the latch with the catch.

10 What is claimed as new is:—

11 1. In a lunch kit including a box having a body and a top hingedly connected at one side by a pintle pin, and a clasp for holding a vacuum walled bottle, or the like in the top, said clasp having a bearing at one end engaging the pintle pin, and a latch at the other, the top of the box having a catch for engagement by the latch, said clasp having the central portion thereof curved to fit the bottle or the like, and having the ends reversely curved to provide resiliency between the central portion and the box, that end of the clasp remote from the bearing having the free end thereof bent to form a finger-piece extending substantially parallel with the adjacent reverse curve in spaced relation for releasing the catch when the finger-piece is pressed inwardly and toward the top.

12 2. In a lunch kit including a box having a body and a top hingedly connected at one side by aligned bearings on the body and top, and a pintle pin engaging the bearings, a clasp for holding a vacuum walled bottle, or the like in the top, said clasp having a bearing at one engaging the pintle pin, and a latch at the other, the top of the box having a catch for engagement by the latch, said clasp having the central portion thereof curved to fit the bottle, or the like, and having the ends reversely curved to provide resiliency between the central portion and the box, that end of the clasp remote from the bearing having the free end thereof bent to form a finger-piece extending substantially parallel with the adjacent reverse curve in spaced relation for releasing the catch when the finger-piece is pressed inwardly and toward the top.

13 3. In a lunch kit including a box having a body and a top, a clasp for holding a vacuum walled bottle or the like in the top, the clasp having the central portion thereof shaped to fit the bottle, and having the ends reversely curved, one end of the clasp being hinged to a wall of the top, and the other end having a latch connection with the opposite wall, the reverse curves providing resiliency between the central portion, the hinge and the latch, the hinged and latch connections of the clasp being at the free edges of the top walls.

14 4. In a lunch kit including a box having a body and a top, a clasp for holding a vacuum walled bottle or the like, in the top, the central portion of the clasp being shaped to fit the bottle and the ends being reversely

15 curved, one end of the clasp being hinged to a wall of the top near the free edge thereof, a latch connection between the clasp and the opposite wall near the free edge thereof, the reverse curves providing resiliency between the central portion, the hinge and the latch, the latch including an integral finger piece substantially parallel with the adjacent curved part and spaced apart therefrom, said finger piece extending at an acute angle to the top wall to enable release thereof by compression against the wall.

16 Signed at Baltimore, in the county of Baltimore and State of Maryland, this 14 day of June, A. D. 1928.
